UNITED STATES PATENT OFFICE.

SAMUEL SMILEY, JR., OF CINCINNATI, OHIO, ASSIGNEE TO THE GLOBE-WERNICKE COMPANY, OF CINCINNATI, OHIO, A CORPORATION OF OHIO.

SHEET GROUP SUSPENSION DEVICE.

Application filed May 10, 1928. Serial No. 276,770.

This invention relates to improved filing means and is particularly directed to a device for group filing of maps, charts, drawings, or reference sheets of any sort. The grouping device herein concerned is adapted to be suspended from a rod or the like and in turn to suspend a segregated lot of sheets therefrom. Various types of attaching tabs or clips for the individual sheets may be used in combination with the present improvement, and one form of commercial type of individual sheet tab particularly adaptable for suspension from the present invention is disclosed in a co-pending application Serial No. 147,568, filed November 10, 1926, by J. W. Fontaine, Patent No. 1,687,859, October 16, 1928.

An object of this invention is to provide a device of the above disclosed nature which readily receives a plurality of sheets in grouped suspension and which is quickly hung from a rack or support.

Another object is to provide a sheet group holder of this type which is of inexpensive construction and of extreme strength and also the provision of convenient means for attaching to the group holder in limited number the clips or tabs of a group of sheets.

Still another object is to provide a suspension means fabricated of cloth and stiffening material suitably lapped and disposed to provide a durable mounting for the common grouping support for the individual sheet-supporting means, the formation of parts being such as to reduce the elements needed to a minimum.

Other objects and certain advantages will be more fully set forth in a description of the accompanying drawings, forming a part of this specification, in which:

Figure 1 is a perspective view of the group suspension means showing a group of individual sheet tabs or clips hung therein.

Figure 2 is a sectional view taken on line 2-2, Figure 1, showing in detail the fabrication of the device.

Figure 3 is a sectional view taken on line 3-3, Figure 2, showing in addition thereto a sheet of material supported therein by means of an individual clip or tab.

Referring to the drawings the device, generally described, comprises a body 5 and a pair of wings or flaps 6 hinged to the body, these wings supporting a binder post 7 traversing the flaps 6, the binder post con-

stituting an attaching rod or suspension element for a group of tabs or clips attached to the margins of the sheets to be segregated by the device.

The base or backing of the body is formed of a rectangular piece or strip 8 of tough, flexible material such as celluloid or pyroxylene.

A length of cloth or adhesive tape 9 is lapped or folded centrally of its length over the upper edge of the piece 7 and is adhesively attached to the sides of the strip. A strip of relatively thick bendable material 10 such as cardboard, is folded centrally and has its folded edge abutting or extending along the lower edge of the celluloid strip 8, the extending halves 11 forming a base for the respective wings or flaps 6 of the device. The continuing lengths of the cloth piece are respectively adhesively attached to the outer faces of these hinged halves and turned or lapped over the lowermost or terminal edges thereof and adhesively secured to the inner faces extending to medial points thereof as at 12.

A line of stitching 13 is run crosswise of the structure along and between the lower edge of the strip 7 and the folded edge of the element 10. Eyelets 14 are secured in the respective formed flaps or wings 6 and are disposed in alignment, providing in the wings a suitable combination support for the binder post 7 traversing the same. These eyelets 14 are held or clamped in position by outwardly turned flanges 15 at each end thereof engaging the respective margins of formed apertures in the flaps or wings, one of the respective flanges of each eyelet being turned after insertion.

The binder post is constructed in two parts. A headed sleeve element 16 is internally threaded and a screw 17 is entered into the internal bore. The binder post thus formed provides a supporting cross rod or suspension means headed at both ends for limiting outward swinging or spreading of the flaps.

The group-holding device as shown is adapted to be supported on a rod or rack, a rod 18 being indicated in this instance in dotted lines. An aperture 19 is formed through the body portion of the device centrally thereof and an incision 20 is provided through the bridge portion between the aperture and the top edge of the device. The

backing or base of the body being flexible permits the spreading of the slit bridge portion and allows the apertured body to be forced into suspended position with the aperture disposed around the rod.

The backing or base is of sufficiently tough material to resist permanent deformation and is sufficiently flexible to allow easy insertion of the device into its suspended or supported position. This particular arrangement for attaching the device in suspension is preferable but not essential in the present invention.

There is a limited spreading movement allowed for the wings due to the use of the double headed floating binding post, this arrangement limiting the number of clips or tabs which may be inserted between the wings and supported on the binder post.

20 This limited group-holding capacity prevents abuse by overload.

The tabs or clips 22 shown, for attaching individual maps or sheets to the contemplated device, form no part of this invention, being claimed in the previously mentioned patent. Generally described, these tabs have their body portions 23 formed in the same manner as the above described bodies for the present invention. The ends 30 of the tape or adhesive coated cloth 24, however, extend down below the lower end of the base strip and these flaps are temporarily adhesively applied to the opposite sides of a strip of commercial tracing linen 25 inserted therebetween.

As shown in Figure 3, the upper margin 26 of the suspended sheet is inserted between the linen strip and the adhesive tape flap, the flap having been raised from its adhesion to the linen strip for insertion of the sheet margin.

It will be readily understood that any desired number of the individual sheet clips or tabs are used on a given sheet and these tabs are placed in the same relative position on the plurality of sheets to be filed in groups so that a number of group holders corresponding to the number of clips or tabs used on an individual sheet is used in the supporting of a group.

Having described my invention, I claim:

1. A group suspension device, comprising, a body portion, a pair of flaps hinged to the lower edge of said body, said body formed for attachment to a support, and a group support element mounted in and between the flaps for receiving a plurality of sheets in suspension between the flaps.

2. A group suspension device, comprising, 60 a body portion formed for attachment to a support, flaps hinged to the lower end of said body, and a rod disposed between the flaps and traversing the same and adapted to receive a plurality of individual sheet support means thereon between said flaps.

3. A group suspension device, comprising, a body portion formed for attachment to a support, flaps hinged to the lower end of said body, and a rod extending between the flaps and traversing the same and adapted to 70 receive a plurality of individual sheet support means thereon between the flaps, said rod headed on both ends to limit spreading of the flaps, whereby the capacity of the device is limited.

75 4. A group suspension device, comprising, a body portion, flaps hinged to the lower edge of said body, an eyelet secured in each flap, said eyelets disposed in alignment, and a rod slidably mounted in the eyelets and adapted to support a plurality of individual support means thereon.

5. A group suspension device, comprising, a base strip of flexible material, a centrally folded strip of bendable material having its 85 folded edge abutting and disposed along the lower edge of the base strip, a strip of adhesive-coated material folded over the upper edge of the base strip and secured to the sides thereof, equal length extensions 90 of the strip being secured to the sides of the folded strip of bendable material, turned over the terminal edges of the folded strip and secured to the inner sides of the folds thereof, and a cross support mounted on the 95 hanger flaps formed by the foregoing assembly.

6. A group suspension device, comprising, a base strip, a folded strip having its upper folded edge disposed adjacent the lower 100 edge of the base strip and a length of cloth adhesively applied surrounding the aforesaid elements binding them together, whereby a pair of depending flaps hinged to a body portion is provided, and means traversing the flaps for suspending a group of sheets therefrom.

7. A group suspension device, comprising, a base strip of flexible material, a folded element formed of stiff foldable material 110 having its folded edge disposed along the lower edge of the base strip, a binding strip of cloth covering the surfaces of the base strip and folded element joining the same together with the folded element to constitute a pair of flaps depending from the base strip, a binder post traversing the flaps, said post forming the support for a plurality of sheets, said body being formed with means for attaching the device to a support. 115

8. A group suspension means, comprising, a base strip, a folded strip having its upper folded edge disposed adjacent the lower edge of the base strip, a length of cloth adhesively applied over the surfaces of the 125 aforesaid elements binding them together, whereby a pair of depending flaps hinged to a body portion is provided, eyelets secured in alignment in the respective flaps, and a cross piece traversing the eyelets in 130

the flaps, said cross piece adapted for suspending a plurality of sheets.

9. A group suspension device, comprising, a base strip, a folded strip having its upper 5 folded edge disposed adjacent the lower edge of the base strip, a length of cloth adhesively applied surrounding the aforesaid elements binding them together, whereby a pair of depending flaps hinged to a body

portion is provided, a line of stitching disposed across the device between the lower edge of the base strip and the folded edge of the folded strip, and means traversing the flaps for suspending a group of sheets therefrom.

In witness whereof, I hereunto subscribe my name.

SAMUEL SMILEY, JR.
